(57) **CLAIM**

The ornamental design for a hair clip, as shown and described.

DESCRIPTION

FIG. 1 is a perspective view of the present invention;

FIG. 2 is a front view thereof;

FIG. 3 is a bottom view thereof;

FIG. 4 is a top view thereof;

FIG. 5 is a left side view thereof;

FIG. 6 is a right side view thereof;

FIG. 7 is an elevational view taken in the direction of the line 7—7 in FIG. 2; and,

FIG. 8 is an elevational view taken in the direction of line 8—8 in FIG. 2.

The broken lines in the drawing are for illustrative purposes only and form no part of the claimed design.
